UNITED STATES PATENT OFFICE

150,886

DESIGN FOR A CHAIR

Walter C. Ross, Belleville, Ill.

Original application December 29, 1945, Serial No. 125,152. Divided and this application February 3, 1947, Serial No. 136,651

Term of patent 14 years

(Cl. D15—1)

To all whom it may concern:

Be it known that I, Walter C. Ross, a citizen of the United States of America, residing in Belleville, in the county of St. Clair, State of Illinois, have invented a new, original, and ornamental Design for a Chair, of which the following is a specification, reference being had to the accompanying drawing, forming a part thereof.

The single view of the drawing illustrates in perspective a chair showing my new design.

The present application is a division of application No. 125,152, now Patent No. D. 146,634.

I claim:

The ornamental design for a chair, as shown.
WALTER C. ROSS.
